US00D379795S

United States Patent [19]

Pitzen et al.

[11] Patent Number: Des. 379,795

[45] Date of Patent: **Jun. 10, 1997

[54] BATTERY HOUSING FOR AN ORTHOPEDIC SURGICAL DEVICE

[75] Inventors: James F. Pitzen, Maplewood; Jeffrey D. Smith, Marine on St. Croix, both of Minn.; Charles E. Alexson, Hayward; Lawrence J. Fenske, Oregon, both of Wis.

[73] Assignee: Minnesota Mining and Manufacturing Company, St. Paul, Minn.

[**] Term: 14 Years

[21] Appl. No.: 46,265

[22] Filed: Nov. 13, 1995

Related U.S. Application Data

[63] Continuation-in-part of Ser. No. 33,712, Jan. 18, 1995, abandoned, which is a continuation of Ser. No. 24,242, Jun. 10, 1994, abandoned.

[51] LOC (6) Cl. 13-02

[52] U.S. Cl. D13/103

[58] Field of Search D13/103; 429/96-100, 429/153

[57] CLAIM

The ornamental design for a battery housing for an orthopedic surgical device, as shown and described.

DESCRIPTION

FIG. 1 is a perspective view of a battery housing for an orthopedic surgical device showing our new design;

FIG. 2 is a left side view thereof, the right side view being a mirror image thereof;

FIG. 3 is a front view thereof;

FIG. 4 is a rear view thereof;

FIG. 5 is a top view thereof; and,

FIG. 6 is a bottom view thereof.
